SPRAYING DEVICE

Harry B. Karter, Garden City, N. Y.

Application July 18, 1933, Serial No. 680,928

13 Claims. (Cl. 299—83)

My invention relates to spray devices of the type employed for emitting an aqueous suspension or solution of a chemical substance, such as, a disinfectant, an insecticide, a water color etc.

5 An object of my invention is the provision of a spray device of the character described which can be attached to the ordinary garden hose and in which the water, in approaching the nozzle, rotates an element composed of the substance

10 to be used in the spray, thereby forming a solution or suspension of that substance depending upon its solubility in water.

A further object of my invention is the provision in such a device of a rotatable element of 15 such configuration that the solution or suspension formed by the passage of water thereover will be of substantially uniform concentration until the substance is entirely consumed.

An additional object of my invention is to so 20 construct the rotatable chemical element that the breaking off of large pieces thereof and the consequent clogging of the spray nozzle will be practically eliminated and that the rotation thereof will be made certain.

25 Still another object of my invention is the provision of means in a device of the character described for preventing the clogging of the spray nozzle by any small lumps of chemical substance which might become separated from the rotatable element.

Further objects and advantages of my invention will appear from the following description of the accompanying drawing in which:

Fig. 1 is a plan view of my spray device with 35 portions thereof in section.

Fig. 2 is a side elevation of my device with the cover separated therefrom and partly in section for the sake of clearness.

Fig. 3 is a section taken through the axis of 40 the framework of the rotatable element.

Fig. 4 is a plan view of the framework of the rotatable element and

Fig. 5 is a plan view of a rotatable element of 45 different configuration.

Referring to the drawing in detail, 1 represents a circular casing having a spindle 2 mounted at its center, a water inlet 3 arranged to direct a stream of water in a direction chordal to the circular casing 1, said inlet being supplied with water by a pipe 4 which has a coupling nut 5 to connect it with an ordinary garden hose and a stop cock 6 for turning the water on and off. Any conventional type of valve can be employed in place of stop cock 6. A handle 7 of any

suitable configuration is arranged between the pipe 4 and the casing 1.

Casing 1 has a water outlet 8 at a point more than 90° removed from the water inlet. The longitudinal axis of this water outlet is normal 60 to the casing 1. Mounted in the outlet 8 in a plane spaced from the circumference of the casing 1 is a screen 12. The space between the screen and the interior of the casing 1 forms a chamber wherein any particles of chemical which may break away from the paddle wheel can be retained 65 out of the path of travel of the paddle wheel until they are broken up or dissolved by the water. The screen prevents these particles from entering into and clogging the nozzle 14 which may be 70 of any conventional type and which is attached to a sleeve 13 mounted on the outlet 8.

Mounted on the spindle 2 is a rotatable element 9 of the chemical substance to be introduced into the water. This element, in its preferred form, has the shape of a paddle wheel. This element has a metal core 10, preferably made of lead or some similar soft heavy metal. Imbedded in the surface of this core and in the chemical substance at equally spaced intervals 75 are perforated vanes 11 shown in dotted lines in Fig. 1. These vanes are preferably made of a light metal, such as, aluminum. Each vane constitutes one paddle of the wheel. The paddles need not be normal to the core, but can be set 80 at an angle thereto or arranged helically thereon, if desired.

The rotatable element of chemical substance is generally molded. This is accomplished by filling the mold of a paste of the desired chemical substance, such as, arsenate of lead or a mixture of arsenate of lead and sulphate of nicotine or any of the common fertilizers, such as, mixed nitrates and phosphates of the alkali metals and ammonia or any water color, kalsomine or whitening etc. The framework composed of core 10 and vanes 11 is immersed in the paste centrally of the mold and the paste is permitted to dry thereon. The moulding is facilitated by the employment of pressure.

100 The circular casing 1 is provided with a cover 15, which carries a glass plate 16, which makes it possible to tell when the chemical substance on the rotatable element is consumed.

In the modification shown in Fig. 5 the vanes 105 of the paddle wheel, instead of being flat pieces of metal, are constructed in the form of cages 17. The sides of these cages are made of a sheet of perforated metal or screen which is bent in the manner shown and the ends of which are brought 110

together and inserted in the soft metal core 18. The bottoms of the cages are likewise made of perforated metal or screen and can be made integral with the sides. Each cage carries a block 5 of chemical substance. When this construction is employed the paddle wheel can be made as a fixed element in the spray device, it being necessary only to replace the blocks of chemical substance. The tops of the cages are open, the 10 blocks being prevented from leaving the cages by the cover plate 16.

It is to be understood that there is no limitation with regard to the material of which the 15 rotatable chemical element is to be made. Any material which is to be employed in an aqueous spray and which dissolves in or suspends in water can be utilized.

It is to be further understood that there is no restriction upon the configuration of the 20 rotatable element except that it must be such that it presents substantially the same surface at all stages of wear. In addition, it must be borne in mind that regardless of what type of device is used, the inlet orifice must have a 25 smaller diameter than the outlet orifice. Of course, the size of the outlet orifice can be regulated by adjustment of the nozzle. As the size of the outlet orifice approaches the size of the inlet orifice the spray becomes finer, but the 30 distance it will travel becomes smaller. Conversely, as the outlet orifice becomes larger, the distance travelled by the spray becomes larger.

Having thus described the nature and objects 35 of my invention and illustrated preferred embodiments thereof, which embodiments are to be taken as illustrative rather than limitative, what I claim as new and useful and desire to secure by Letters Patent is:

1. In a device of the character described, in 40 combination, a mixing chamber, a water inlet in said chamber, a water outlet spaced from said water inlet and a rotatable element mounted in said mixing chamber between said water inlet and said water outlet comprising a metal core provided with vanes, said core and vanes being covered with a chemical substance adapted to be dispersed in water and said water inlet being so arranged with respect to said vanes that the flow of water from said inlet impinges on said vanes successively thereby causing rotation of the 45 rotatable element.

2. In a device of the character described, in 50 combination, a mixing chamber, a water inlet in said chamber, a water outlet spaced from said water inlet and a rotatable element mounted in said mixing chamber between said water inlet and said water outlet comprising a metal core provided with perforated metal vanes, said core and perforated metal vanes being covered with a chemical substance adapted to be dispersed in water and said water inlet being so arranged with respect to said vanes that the flow of water from said inlet impinges on said vanes successively thereby causing rotation of the 55 rotatable element.

3. In a device of the character described, in 60 combination, a mixing chamber, a water inlet in said chamber, a water outlet spaced from said water inlet and a rotatable element mounted in said mixing chamber between said water inlet and said water outlet comprising a core of soft heavy metal provided with vanes, said core and vanes being covered with a chemical substance adapted to be dispersed in water and said water inlet being so arranged with respect to said 65

vanes that the flow of water from said inlet impinges on said vanes successively thereby causing rotation of the rotatable element.

4. In a device of the character described, in 70 combination, a mixing chamber, a water inlet in said chamber, a water outlet spaced from said water inlet and a rotatable element mounted in said mixing chamber between said water inlet and said water outlet comprising a core of soft heavy metal provided with perforated light metal vanes, said core and vanes being covered with a chemical substance adapted to be dispersed in water and said water inlet being so arranged with respect to said vanes that the flow of water from said inlet impinges on said vanes successively thereby causing rotation of the rotatable element.

5. In a device of the character described, in 75 combination, a mixing chamber, a water inlet in said chamber, a water outlet spaced from said water inlet and a rotatable paddle wheel mounted in said mixing chamber between said water inlet and said water outlet comprising a metal core provided with vanes constituting paddles, said core and vanes being covered with a substantially 80 uniform layer of a chemical substance adapted to be dispersed in water and said water inlet being so arranged with respect to said vanes that the flow of water from said inlet impinges on said vanes successively thereby causing rotation of the rotatable element.

6. In a device of the character described, in 85 combination, a mixing chamber, a water inlet in said chamber, a water outlet spaced from said water inlet and a rotatable paddle wheel mounted in said mixing chamber between said water inlet and said water outlet comprising a metal core provided with perforated metal vanes constituting paddles, said core and vanes being covered with a substantially 90 uniform layer of a chemical substance adapted to be dispersed in water and said water inlet being so arranged with respect to said vanes that the flow of water from said inlet impinges on said vanes successively thereby causing rotation of the 95 rotatable element.

7. In a device of the character described, in 100 combination, a mixing chamber, a water inlet in said chamber, a water outlet spaced from said water inlet and a rotatable paddle wheel mounted in said mixing chamber between said water inlet and said water outlet comprising a core of soft heavy metal provided with vanes constituting paddles, said core and vanes being covered with a substantially 105 uniform layer of a chemical substance adapted to be dispersed in water and said water inlet being so arranged with respect to said vanes that the flow of water from said inlet impinges on said vanes successively thereby causing rotation of the 110 rotatable element.

8. As an article of manufacture, a rotatable 115 body comprising a metallic axial member provided with vanes and a coating on said axial member and vanes composed of a chemical substance adapted to be dispersed in water.

9. As an article of manufacture, a rotatable 120 body comprising an axial member of soft heavy metal provided with vanes and a coating on said axial member and vanes composed of a chemical substance adapted to be dispersed in water.

10. As an article of manufacture, a rotatable 125 body comprising an axial member of soft heavy metal provided with perforated light metal vanes and a coating on said axial member and vanes composed of a chemical substance adapted to be dispersed in water.

11. As an article of manufacture, a paddle wheel having a metal core and having its paddles composed of a chemical substance adapted to be dispersed in water and provided with internal substantially centrally located reenforcement in the form of vanes extending from said metal core.
12. As an article of manufacture, a paddle wheel having a soft heavy metal core and having its paddles composed of a chemical substance adapted to be dispersed in water and provided with internal substantially centrally located reenforcement in the form of perforated light metal vanes extending from said metal core.
- 10 to be dispersed in water and provided with internal substantially centrally located reenforce-

ment in the form of vanes extending from said metal core.

13. As an article of manufacture, a paddle wheel having a soft heavy metal core and having its paddles composed of a chemical substance adapted to be dispersed in water and provided with internal substantially centrally located reenforcement in the form of perforated light metal vanes extending from said metal core.
